FOLDING TABLE

Roy O. Cuffel, Los Angeles, Calif.

Application July 29, 1933, Serial No. 682,814

6 Claims. (Cl. 311—87)

This invention relates to tables and more particularly to folding leg tables used for card games or the like.

The above type of table now in general use tends to wobble or in some cases collapse when the legs are opened or extended.

It is therefore the object of the present invention to provide a table of the character described that will be substantial and rigid when the legs are extended.

Another object is to provide a table of the character described in which the legs may be quickly opened or closed and automatically lock when extended.

Another object is to provide a folding leg table having a novel locking mechanism which will firmly hold the legs in open or extended position.

A further object is to provide a folding leg table so constructed that the legs can only be folded in proper order in overlapping relation to each other.

Other objects and advantages will be apparent from the following description, reference being had to the accompanying drawings, in which:

Fig. 1 is a side elevation of the folding leg table, parts being broken away and shown in section.

Fig. 2 is a vertical section taken on line 2—2 of Fig. 1.

Fig. 3 is a bottom plan view.

Fig. 4 is a view similar to Fig. 3 but showing the legs in folded position.

Fig. 5 is a horizontal section taken on line 5—5 of Fig. 4.

Fig. 6 is an enlarged horizontal section taken on line 6—6 of Fig. 3.

Fig. 7 is a section taken on line 7—7 of Fig. 4.

Fig. 8 is a detail section taken through the latch mechanism as indicated by line 8—8 of Figs. 3 and 10.

Fig. 9 is a view analogous to Fig. 8 showing the position assumed by the latches during folding of the table legs.

Fig. 10 is a fragmentary plan view of the latch mechanism.

Fig. 11 is a transverse section taken on line 11—11 of Fig. 8.

Referring more specifically to the drawings, the table top designated at 10 is of square shape and provided with an apron 11. Pivotally connected to the opposite side members 12 of the apron or suitable pins 13 are oppositely disposed pairs of legs 14 and 15 respectively, the legs of each pair being joined together by a cross piece 16 in order that they will turn in unison, while

the pins 13 are disposed in horizontal planes in offset relation so that the legs of one pair will fold upon those of the other pair.

Connected to the legs 14 is a brace 18 and to legs 15 a brace 19, which braces serve to hold said legs in extended or open position as shown in Figs. 1 and 2. Each brace is substantially V-shaped in elevation and preferably formed of a single piece of steel wire. The arms of the braces have outwardly turned ends 20 which extend into and are pivoted in aligned openings formed in the legs at a point below the pivot pins 13, while their inner or free ends overlap, as clearly shown in Figs. 3 and 10. In the present instance the brace 19 extends over that of brace 18.

This overlapping permits opening and closing of the legs without interference or contact of one brace with the other during such movement, and is an important feature of the invention.

Secured to the intermediate portions 25 of the braces 18 and 19 are eyes or loops 21 that slidably engage guide rods 22 and 23 respectively, that are secured to a rail 24 formed integral with or secured to the top 10.

Guide rods 22 and 23 are provided to guide the braces 18 and 19 into engagement with a locking or latch mechanism, generally designated at 26 that serves to hold or retain the legs in open or extended position and is constructed in a manner hereinafter described.

As previously referred to, the legs of one pair are arranged to fold on those of the other pair, in the present instance, the legs 15 upon the legs 14, and in order to insure such movement or prevent closing otherwise the guide member 22 is provided with a stop or abutment 28.

The guide rod 22 is formed of spring metal and is secured to the rail 24 by a screw or the like 29 and has formed therein an upraised portion 30 adjacent the screw 29, while the stop or abutment 28 is formed in its outer end portion and is disposed in a slot 32 formed in the rail 24. When the legs of both pair are opened the abutment will be raised or lifted so that it projects above the surface of the rail by the intermediate portion 25 of the brace 18 (which then extends under the guide rod 22) as shown in Fig. 6.

When in this position the legs 15 cannot be closed for the reason that should an attempt be made to do so such movement would be stopped or limited by contact of the intermediate portion 25 of the brace 19 with the face of the abutment 28.

On the other hand when or after the legs 14

have been closed the abutment will be moved back in the slot 32 due to the spring action of the rod 22 and the intermediate portion 25 of the brace 18 then engaging the upraised portion 30 of the bar. Thereafter, the legs 15 may be closed. Outward movement of the braces is limited by stops 33 secured to the rail 24.

Referring to Figs. 9 to 11 inclusive, the locking mechanism 26 consists of a pair of latches 36 that are disposed in a slot 37 formed in the rail 24 midway of its ends and are pivotally mounted on pins 38 extending through said slot.

Each latch comprises a lever arm 39 and a finger or latch jaw 40 having a cam face 41 formed thereon, the lever and jaw being disposed at substantially right angles to each other, between which are formed a recess or indent indicated at 42, the latches being preferably formed of a single piece of sheet metal, die stamped into the shape above described.

The latches are mounted on the pivot pins 38 with the jaws 40 projecting in opposite directions and when thus positioned the recess 42 of one latch accommodates the pin of the other, thereby permitting independent pivotal movement, the latches being interconnected at a point below the pivot pins 38 by a retractile coil spring 43 which serves to restore the same to normal position.

Pivotal connected as indicated at 44 to the lever arms 39 of the latches are detents 45 having inwardly turned ends 46 that engage and limit movement of said detents on the arms.

The detents serve to disengage the portions 25 of the braces 18 and 19 from the latches in a manner later described.

During opening of the legs the intermediate portions 25 of the braces engage the cam faces 41 of the jaws and depress the same as shown in Fig. 9, i. e. until the intermediate portions 40 pass thereover, whereupon the jaws snap over the same (by action of the spring), resulting in locking the braces as shown in Fig. 10.

When locked as above described the intermediate portions of the braces occupy the recesses 42 and are engaged by the faces 48 of the jaws of the latches and thereby firmly hold the legs in extended position.

In releasing or unlocking latches, the detents are adapted to be manually gripped, i. e. between the thumb and first finger, the action of which simultaneously tilts the latches and brings the detents into engagement with the intermediate portions 25 of each brace. Continued movement of the latches releases the jaws from intermediate portion 25 of the braces, whereupon the detents throw the same clear of the latches. The legs may then be closed as above described.

It will be noted that due to the pivotal mounting of the latches, relative position of the lever arms and detents thereon, a quick and positive release of the braces from the locking mechanism is effected.

From the foregoing it will be seen that the table is of substantial construction, may be easily and cheaply produced, also, that when the legs are opened and locked, a construction is provided that is substantially as strong as that of a usual rigid leg table.

70 I claim:

1. A folding leg table comprising a top, two pairs of legs pivotally connected to said top and arranged to fold one upon the other, a locking mechanism including a pair of pivoted latches mounted on the underside of said top, braces pivotally connected to the legs of each pair, a pair

of guide rods secured to the underside of said top for guiding the braces into engagement with latches of said locking mechanism when each pair of said legs are fully extended, one of said guide rods having an abutment formed thereon for preventing improper closing of said legs so that they may be only folded one on the other in overlapping relation.

2. A folding leg table comprising a table top, two pairs of legs pivotally connected to the table top, braces pivotally connected to said legs, a pair of longitudinally disposed guide rods secured to the table top, means secured to each of said braces intermediate their ends and slidably engaging said guide rods for holding the same in engagement therewith, a locking mechanism for holding the legs in extended position comprising a pair of pivotally mounted latches, each latch having a lever arm and a jaw provided with a cam surface disposed in the path traversed by the intermediate portions of said braces during opening of the legs, a detent pivotally connected to the arm of each latch and arranged to engage and release the intermediate portions of said braces from the latches, and spring means interconnecting said latches for holding the same in engagement with the braces.

3. A folding leg table comprising a table top, two pairs of legs pivotally connected to the table top, braces pivotally connected to said legs, a pair of longitudinally disposed guide rods secured to the table top, means secured to each of said braces intermediate their ends and slidably engaging said guide bars for holding the same in engagement therewith, a locking mechanism for holding the legs in extended position comprising a pair of latches disposed in the slot formed in said rail and pivotally mounted therein, each latch having a lever arm and jaw provided with a cam face, there being an indent formed in each latch between the lever arm and jaw, said latches being mounted on the pivotal connections with the jaws projecting in opposite directions and their cam faces disposed in the path traversed by the intermediate portions of the braces during opening of the legs, a detent pivotally connected to the arm of each latch and arranged to engage and release the intermediate portions of said braces from the latches, and a retractile coil spring interconnecting said latches, for holding the same in engagement with the braces.

4. A folding leg table comprising a table top, two pairs of legs pivotally connected to the table top, a rail having a slot therein midway of its ends secured to the underside of the table top, braces pivotally connected to said legs, a pair of longitudinally disposed guide rods secured to said rail, means secured to each of said braces intermediate their ends and slidably engaging said guide rods, a locking mechanism for holding the legs in extended position comprising a pair of latches disposed in the slot formed in said rail and pivotally mounted therein, each latch having a lever arm and a jaw provided with a cam surface projecting beyond the face of said rail with the cam surface disposed in the path traversed by the intermediate portions of said braces during opening of the legs, a detent pivotally connected to the arm of each latch and arranged to engage and release the intermediate portions of said braces from the latches, and spring means interconnecting said latches for holding the same in engagement with the braces.

5. A folding leg table comprising a table top, a

5 rail having a recess formed therein secured to the underside of the top, two pairs of legs pivotally connected to the table top and arranged to fold one upon the other, V-shaped braces pivotally connected to each pair of said legs with their free ends in overlapping relation to each other, a locking mechanism for holding said legs in extended position comprising a pair of latches disposed in a recess formed in said rail and pivotally mounted therein, each latch having a lever arm and jaw provided with a cam face projecting beyond the surface of the rail, there being an indent formed in each latch between the lever arm and jaw, said latches being mounted on the pivotal connections with the jaws projecting in opposite directions and their cam faces disposed in the path traversed by the intermediate portions of the braces during opening of the legs, a detent pivotally connected to the arm of each latch and arranged to engage and release the intermediate portions of said braces from the latches, a retractile coil spring interconnecting said latches for holding the same in engagement with the braces, a guide rod rigidly secured to said rail,

10 a second guide rod formed of spring metal secured at one end thereof to said rail and having an abutment formed thereon for preventing improper closing of the legs, and means secured to said braces and slidably engaging said guide rods for guiding the same into engagement with the latches of said locking mechanism.

15 6. A folding leg table comprising a table top, two pairs of legs pivotally connected to the table top and arranged to fold one upon the other, a brace pivotally connected to each pair of said legs, a locking mechanism for holding said legs in extended position comprising a pair of pivotally mounted latches, a guide rod rigidly secured to said table top, a second guide rod formed of 20 spring metal secured at one end thereof to said table top and having an abutment formed thereon for preventing improper closing of the legs, and means secured to said braces and slidably engaging said guide rods for guiding the same into engagement with the latches of said locking mechanism.

ROY O. CUFFEL.
